J.S. 1091

Garrison Smith & Henry Brown of Philadelphia Pa.

Assignors to

Libranch Mc Dowell & Co. of same place.

Letters Patent No. 1072. dated Dec. 14th, 1858.

The schedule referred to in these Letters Patent and making part of the same,

To all whom it may concern:

Be it known that we Garrison Smith and Henry Brown, both of the City and County of Philadelphia and State of Pennsylvania, have invented or produced a new and original design for a parlor stove, termed the "Corn"; and we do hereby declare the following to be a full and exact description of the same, reference being had to the accompanying drawing, in which

Fig: 1. represents a front view.

Fig: 2. a side view; and

Fig: 3. a rear view of our new design for parlor stoves.

Fig: 4. is a view of the cap of the stove.

Fig: 5. a view of the upper plate of the base,

Fig: 6. a view of the bottom plate of the base, and

Fig: 7. a full-sized, sectional view of the molding, on the edge of the bottom plate of the stove.

The body A. of the stove is made of sheet iron, and is of an oval form, as is also the flue B. at the rear. The top plate of the stove is also of an oval form, adapted to the body, and is edged with an open work molding, which surrounds a series of foliated ornaments.

A square ornamented frame D. is secured to the body of the stove, and to this frame is hung a door E, having two openings surrounded with foliated ornaments.

The base consists of a front plate G, with an opening covered by the ash pit door M, the two side plates H, the curved rear plate F, the top plate I, and bottom plate J.

The front, side and back plates, as well as the ash pit door, are ornamented with foliage in bas-relief, all the ornaments being of a similar character.

1072

Des. 1072

The top plate I, is edged with a plain molding, with four curved projections, having each a foliated ornament, and the bottom plate is edged with an ornamental foliated molding, a full sized view of which is represented in Fig. 2.

We claim and desire to secure by Letters Patent,

The combination of ornamental figures and forms, represented in and by the accompanying drawing, forming together an ornamental design for the plates of parlor stoves.

In testimony whereof, we have signed our names to this specification in the presence of ten subscribing witnesses.

Witnesses.
